UNITED STATES PATENT OFFICE.

PAUL J. HACKETT, OF SEATTLE, WASHINGTON, ASSIGNOR TO UNIVERSAL HIGH POWER
TELEPHONE COMPANY, OF KING COUNTY, WASHINGTON.

DIFFERENTIAL MICROPHONE.

1,274,035.

Specification of Letters Patent. Patented July 30, 1918.

Application filed October 23, 1916. Serial No. 127,109.

To all whom it may concern:

Be it known that I, PAUL J. HACKETT, a citizen of the United States, and a resident of Seattle, in the county of King and State of Washington, have invented certain new and useful Improvements in Differential Microphones, of which the following is a full, true, and exact specification.

My invention relates to improvements in differential microphones and has for its principal object to improve upon the construction of microphones and carbon cups as illustrated in my previous application, Serial No. 68,109, filed December 22nd, 1915, in that a carbon cup is provided which is non-packing, air tight and therefore does not deteriorate. Another object of my device is to provide a simple and novel construction which embodies a metallic dia-

phragm having carbon cups adjustably secured one on each side thereof. In microphones for high power work attempts have been made to use carbon diaphragms but the excessive breakage in thin carbon dia-

phragms of relatively large diameter has prevented their extensive use. The usual carbon cups give serious trouble from packing of the carbon granules, due to excessive heat, absorption of moisture and lack of fa-

cilities for expansion. The above disadvantages have been overcome in my device.

Other objects will appear as my invention is more fully explained in the following specifications, illustrated in the accompanying drawing and pointed out in the appended claims.

In the drawings Figure 1 is a plan view of my device. Fig. 2 is a central cross section of same. Fig. 3 is an enlarged cross

sectional view of one of my carbon cups.

Referring more particularly to the drawings, numeral 1 indicates a diaphragm housing which has an annular ring 2 integral therewith. A metallic diaphragm 3 which is housed by a felt ring 4 rests within ring 2 and against housing 1. The diaphragm 3 may be held in place by any approved clamping means. The upper portion of housing 1 is provided with a threaded mouth piece 5 within which the mouth piece is secured. A cone deflector 7 is integral with housing 1 and is centrally located within the said mouth piece 6. A series of perforations 8 are cut in the housing between the

cone deflector 7 and the mouth piece 6. A cylindrical shell 9 extends downwardly from housing 1 to a point close to diaphragm 3 and is of such diameter as to lie within the circle of holes 8. A bridge 10 is secured to ring 2 and crosses the diaphragm diametricaly. A clamp block 11 is mounted upon bridge 10 and is insulated therefrom. A pair of similar carbon cups are mounted one on either side of diaphragm 3. One of the carbon cups fits within the cylindrical shell 9. Each of the cups is provided with a stem 12 one of which fits slidably within a cored opening 13 in deflector 7 while the other passes slidably through bridge 10 and block 11. Each carbon cup includes a main cup 14 which is integral with stem 12 and which is threaded internally. A carbon disk 15 is held in the bottom of cup 14 by means of a threaded nipple 16 which screws within cup 14. Nipple 16 extends beyond the open end 75 of cup 14 and receives a threaded flange 17. A mica disk 18 is clamped between the nipple and the threaded flange 17. A copper plated carbon disk 19 is secured against the inside of mica diaphragm 18 by means of a 80 threaded rod 20 and a button 21. The outer ends of rods 20 screw into a common nut 22 which is used to connect the cups and to clamp the diaphragm 3 between the nut and one of the buttons 21. The space within the 85 carbon cups adjacent the inner surface of nipple 16 and the mica disk 18 I fill with fluffy asbestos which is held in place by small fragments and small threads being clamped between the ends of the nipple 16 and the 90 carbon disk 15 and diaphragm 18. The remaining space within the cup is filled with granular carbon. The presence of the fluffy asbestos prevents packing of the carbon and allows for expansion of the carbon 95 due to heating. It will be noted that my carbon cups are made substantially air tight and that the carbon granules are protected from the action of atmosphere and moisture. My carbon cups are extremely simple 100 in construction, cheap of manufacture and easy to assemble, therefore providing an efficient and novel construction.

While I have shown a particular form of embodiment of my invention, I am aware 105 that many minor changes therein will readily suggest themselves to others skilled in the art without departing from the spirit

and scope of the invention, and I therefore desire to avoid being limited to the exact form shown and described.

Having described my invention, what I claim as new and desire to protect by Letters Patent, is—

1. The combination in a microphone which includes a diaphragm with a resilient insulating ring about its periphery and carbon 10 cups disposed on opposite sides thereof, the movable electrodes of which are fixed to said diaphragm, of means for holding said diaphragm and cups in an operative position, said means including a face plate threaded 15 to receive a mouth piece, said face plate supporting the said diaphragm at its periphery; a conical shaped piece recessed to receive one of said cups disposed at the center of said face plate, there being apertures through 20 said face plate disposed about the base of said conical shaped piece, said apertures communicating with the said mouth piece and being adjacent the diaphragm, and a bridge attached to the back of said face plate 25 with an insulating lug thereon and bored out to receive another of said cups.

2. In a microphone having a pair of similar cups containing granules of conductive

material, a movable diaphragm attached to said cups in common, the combination in 30 each of said cups of an internally threaded main cup having a stem, a polished carbon disk within the bottom of said internally threaded main cup, a threaded nipple within said main cup and extending beyond the end thereof, a mica diaphragm adjacent the outer end of said nipple, said mica diaphragm supporting a movable electrode, said movable electrode including a carbon disk polished on its face and bored through 40 the center to receive a stud whose head is countersunk into the polished surface of the last mentioned disk, said stud passing through the said mica diaphragm and screwing through a back plate forming a support 45 for the last mentioned carbon disk, and the other surfaces of said carbon disk being electro-plated, a threaded flange screwed on the outer end of said nipple and against said mica diaphragm, and a fluffy asbestos packing ring within said nipple and adjacent said mica diaphragm, whereby the granular conductive material contained within the cup is allowed to expand and packing is 50 prevented.

PAUL J. HACKETT.
